UNITED STATES PATENT OFFICE

2,564,813

GROWING DOLL

William Robert Moyers, Sr., St. Augustine, Fla.

Application December 26, 1947, Serial No. 793,965

3 Claims. (Cl. 46—119)

1

This invention relates to a growing doll. It is an object of the present invention to provide a doll construction formed of separable parts which can be expanded and simple mechanism for slowly expanding the same whereby to simulate a growing effect of the doll over an extended period of time.

Other objects of the present invention are to provide a growing doll which is of simple construction, inexpensive to manufacture, of minimum parts, easy to set, and efficient in operation.

For a better understanding of the invention, reference is made to the following detailed description taken in connection with the accompanying drawing, in which

Fig. 1 is a front elevational view of the doll embodying the features of the present invention with the separable parts retracted,

Fig. 2 is a rear elevational view of the doll with the parts extended to substantially full growth and with portions broken away to show the operable parts thereof,

Fig. 3 is a perspective view of the clock motor,

Fig. 4 is a fragmentary sectional view taken on line 4—4 of Fig. 2,

Fig. 5 is a transverse sectional view taken on line 5—5 of Fig. 2,

Fig. 6 is a fragmentary and sectional view taken on line 6—6 of Fig. 2.

Referring now to the figures, 10 represents a set of legs forming one part and 11 represents the upper part or other part of the body on which there is a head 12 and arms 13. The upper part 11 has a large recess 14 into which the upper portion of the leg set 10 may be retracted. The parts 10 and 11 may be formed of rubber or other doll material.

In the leg set 10 are spaced holes 15 into the bottom of which there is extended and fixed respectively rods 16. In the body part 11 are long holes 17 corresponding respectively to the holes 15. Intermediate the length of each hole 17 is a shoulder 18 against which a washer 19 on the rod 16 is forced by a spring 21 surrounding the rod 16 and tending to support the parts 10 and 11. The washer 19 is held in place on the rod 16 by a pin 22. The washer 19 lies in the hole 17 and against the shoulder 18 and lifts the part 11 when acted upon by the spring 21.

When the parts are forced together so that the doll will be of short length as shown in Figure 1, the springs 21 will be compressed and the rods 16 will extend to the upper ends of the openings 17.

To retain the parts together and to permit their slow separation or their growing effect, there is provided a clock motor 24 having a drum 25 with a string 26 which is connected to an eye 27 fixed in a recess 28 in the upper end of the leg set 10. This clock motor is wound by a turn knob 31 and as the motor operates portions of the string 26 will be let out and the parts will be separated slowly by the springs 21. The clock spring can be set by a turn knob 29.

The clock motor is fitted into a recess 33 in 65

2

the back of the part 11 and is secured there within by screws 34 entering holes 35 in the respective corners of the clock and threaded into the body part 11.

5 While various changes may be made in the detail construction, it shall be understood that such changes shall be within the spirit and scope of the present invention as defined by the appended claims.

10 I claim:

1. A growing doll comprising separable body parts, one of said parts having a large recess into which the other part may be extended, openings in the parts, guide rods extending between

15 and through the corresponding openings of the respective parts, springs acting upon the rods to separate the parts, a clock motor device secured to one part and connected to the other part to gradually permit the extension of the body parts by the springs whereby to simulate a growing effect of the doll.

2. A growing doll comprising separable body parts, one of said parts having a large recess into which the other part may be extended, openings in the parts, guide rods extending between

25 and through the corresponding openings of the respective parts, springs acting upon the rods to separate the parts, a clock motor device secured to one part and connected to the other part to gradually permit the extension of the body parts by the springs whereby to simulate a growing effect of the doll.

30 3. A growing doll comprising separable body parts, one of said parts having a large recess into which the other part may be extended, openings in the parts, guide rods extending between and through the corresponding openings of the respective parts, springs acting upon the rods to separate the parts, a clock motor device secured to one part and connected to the other part to gradually permit the extension of the body parts by the springs whereby to simulate a growing effect of the doll, the openings in one of the parts having a shoulder, a washer extending about the respective rods and engageable with the shoulders of the respective openings, means for retaining the washers on the rods and the springs reacting against the washers.

35 4. A growing doll comprising separable body parts, one of said parts having a large recess into which the other part may be extended, openings in the parts, guide rods extending between and through the corresponding openings of the respective parts, springs acting upon the rods to separate the parts, a clock motor device secured to one part and connected to the other part to gradually permit the extension of the body parts by the springs whereby to simulate a growing effect of the doll, said timing device comprising a string, a clock motor, a drum, on the clock

45 motor and said string extending over the drum, an eye connected to the other part and the string connected to the eye.

50 WILLIAM ROBERT MOYERS, SR.
